SAFETY TIMING TRAFFIC LIGHT

Filed Oct. 2, 1940.

UNITED STATES PATENT OFFICE

2,271,526

SAFETY TIMING TRAFFIC LIGHT

Eleanor McGuinness, Jackson Heights, N. Y.

Application October 2, 1940, Serial No. 359,354

10 Claims. (Cl. 177—337)

This invention relates to new and useful improvements in a safety timing traffic light.

More specifically the invention proposes the construction and application of a safety timing traffic light for location upon the top of a conventionally constructed traffic light signal and operative during the time the red light of the traffic light is lit for the purpose of indicating to pedestrians and to motorists the amount of time still to elapse before the light changes from red to green or vice versa. Still further the invention proposes to characterize the timing traffic light by a vertically extended tube into which a signal fluid is adapted to be pumped to slowly rise within the tube from the bottom upwards and to be controlled by the red light circuit for the purpose of indicating the amount of time remaining before the light changes.

Still further the invention proposes the application of a red light to the bottom of the tube which is adapted to be lit during the time the signal fluid is rising within the tube for the purpose of illuminating the same in a manner to make the device visible at night.

A further object of this invention proposes the application of a means for quickly drawing the fluid out of the tube during the time the signal is green for the purpose of resetting the device to again repeat its normal operation when the light again turns red.

A further object of this invention is the construction of a signal safety timing traffic light and device for application upon a conventional traffic light having one operative side or the construction of a double superimposed safety timing traffic light mounted upon a conventionally constructed traffic light having four operative sides in a manner to permit the device to be used upon conventionally constructed traffic lights of different types.

A further object of this invention is the construction of a safety timing traffic light as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a safety timing traffic light constructed in accordance with this

invention and applied to the top of a conventionally constructed traffic signal light.

Fig. 2 is an enlarged elevational view of a portion of Fig. 1.

5 Fig. 3 is a vertical sectional view of a portion of Fig. 2.

Fig. 4 is an enlarged vertical sectional view on the line 4—4 of Fig. 2.

10 Fig. 5 is an enlarged horizontal sectional view on the line 5—5 of Fig. 3.

Fig. 5A is a vertical sectional view taken on the line 5A—5A of Fig. 5.

Fig. 6 is a schematic wiring diagram of the device.

15 Fig. 7 is a view similar to Fig. 2 but illustrating a modification of the invention.

Fig. 8 is a view similar to Fig. 1 but illustrating a still further modification of the invention.

The safety timing traffic light, according to this invention, is to be used in combination with a conventionally constructed traffic light signal consisting of a casing 10 having a green light 11 and a red light 12. An electric circuit 13 is provided for controlling the illumination of the green light 11 and a like circuit 14 is provided for controlling the illumination of the red light 12. The association of the circuits 13 and 14 is such that they are connected with a conventional means, not shown in the drawing, which will 25 cause the red and green lights to be successively lit and extinguished for predetermined periods of time for the purpose of indicating to pedestrians and motorists when they are to proceed and when they are to stop.

30 35 The safety timing traffic light, is characterized by a tube 15 constructed of clear glass and having a wavy contour. The tube 15 is extended vertically upwards from the top wall of the casing 10. A horizontal wall 16 is positioned above

40 the top wall of the casing 10 and is held in position thereon by means of several legs 17. The tube 15 is located between the adjacent faces of the top wall of the casing 10 and the bottom face of the horizontal wall 16. A tank 18 is mounted

45 within the casing 10 adjacent the top wall thereof and is provided for storing a red signal fluid 19. A liquid pump 20 is also mounted within the casing 10 adjacent the top wall thereof and is connected with the tank 18 by means of a pipe

50 55 21. The operative mechanism of the liquid pump is connected in the red light circuit 14 for the purpose of setting the pump in operation when the red light 12 of the traffic light signal is lit. The liquid pump 20 is of a type capable of forcing a liquid to slowly rise within the tube 15. The

bottom end of the glass tube 15 is connected with a fork element 22 one arm of which is provided with a pipe 23 which connects with the liquid pump 20.

When the liquid pump 20 is set in operation when the red light 12 is lit it draws signal fluid from the tank 18 and pumps the same through the pipe 23 to cause the same to rise slowly within the tube 15. The liquid pump 20 is of an adjustable nature and is adapted to be adjusted to pump a sufficient quantity of signal fluid to rise slowly from the bottom to the top of the tube 15 during the time the red light 12 is lit. The construction is such that when the signal fluid 19 reaches the top of the tube 15 the liquid pump is to stop operating when the red light goes out and at which time the green light 11 becomes lit.

The other arm of the fork element 22 is connected to a pipe 24 which has its free end connected to the tank 18 for acting as a drain, for conveying the signal fluid 19 pumped into the tube 15 back to the tank 18 during the time the green light is lit.

A valve is mounted in the arm of the fork element 22 which is connected with the drain pipe 24 and is arranged for closing the drain during the time the liquid pump 20 is in operation. This valve is characterized by a turnably mounted cock 25 located within the arm of the fork element 22. The cock 25 is provided with a passage 25^a which is adapted to be successively aligned and disaligned with the passage of the arm through the fork element 22 for opening and closing this passage. The cock 25 is provided with an outwardly extended stem 26 upon the outer end of which a radially extended arm 27 is fixedly mounted.

A means is connected with the arm 27 for the purpose of turning the stem 26 to move the cock 25 into an operative and inoperative position. This means comprises a solenoid 28 mounted upon the top of the tank 18. The solenoid 28 comprises a coil 28^a mounted in the green light circuit 13. A bar 28^b extends through the coil 28^a and has its free end attached to the free end of the radial arm 27 for drawing the arm 27 to a position in which the passage 25^a through the cock 25 will be aligned with the passage through the arm of the fork element 22 to permit the liquid to be drawn back into the tank 18. A spring 29 is provided for drawing the radial arm 27 into a position in which the passage 25^a through the cock 25 will be disaligned with relation to the passage through the arm of the fork element 22 for closing this passage the minute the green light circuit goes out, de-energizing the coil 28^a of the solenoid.

A means is provided for creating a partial vacuum within the tank 18 for the purpose of quickly sucking the signal fluid 19 out of the tube 15 the minute the valve 25 is moved to its open position. This means comprises a suction pump 30 capable of drawing air from a closed chamber to set up a partial vacuum and positioned adjacent the liquid pump and which is also mounted in the red light circuit for sucking air out of the tank 18 during the time the red light 12 is lit. When the red light 12 goes out and the green light 11 is illuminated, the valve 25 will move to its open position and the vacuum created within the tank 18 will quickly suck the signal fluid 19 out of the tube 15 through the pipe 24 to discharge into

the tank 18. The suction pump 30 is connected with the tank 18 by means of a pipe 31.

A means is also provided for illuminating the liquid fluid 19 during the time the red light 12 is lit for the purpose of illuminating the rising red signal fluid 19 to make the same visible at night. This means comprises a red light 32 mounted within the bottom portion of the tube 15 and connected by means of leads 33 with the red light circuit 14 for causing the same to be lit during the time the red light 12 is lit. This lamp 32 is mounted within a socket 34 positioned within a rubber element 35. The back of the tube 15 adjacent the bottom thereof is provided with an opening 36 into which the rubber element 35 is adapted to be extended and which acts as a stopper for preventing the loss of signal fluid therethrough. This rubber element 35 further tightly and waterproofy engages about the base of the lamp 32 for the purpose of preventing the fluid from entering the socket 34 causing a short circuit.

The device is further provided with a means for collecting signal fluid 19 which should be discharged from the top of the tube 15 to prevent the spilling and loss thereof. The top of the tube 15 is open to prevent air from being entrapped therein and is connected with a return pipe 37 which extends into the top of the casing 10 and is connected with an auxiliary tank 38. Any signal fluid 19 which spills from the top of the tube 15 will pass down through the pipe 37 and enter the auxiliary tank 38. The auxiliary tank 38 is connected with the tank 18 by means of a pipe 39. A manually controllable valve 40 is positioned in the pipe 39 for preventing the suction created within the tank 18 from drawing the fluid collected within the auxiliary tank 38 into the tank 18. If it were not for this valve 40, the interior of the auxiliary tank 38 would be connected with the top of the tube 15 and suction created therein would draw the signal fluid 19 upwards within the tube 15 faster than it is being pumped by the liquid pump 30. This valve 40 is adapted to be opened during adjustment periods for the purpose of permitting the fluid gathered within the auxiliary tank 38 to be discharged into the tank 18.

The lamp 32 may be of any other danger signalling color, such as yellow, amber, etc.

The operation of this form of the invention is as follows:

The tank 18 is partially filled with a sufficient quantity of signal fluid 19 to fill the tube 15 therewith. The liquid pump 20, suction pump 30, and red lamp 32 are mounted in the red light circuit 14 and the coil 28^a of the solenoid 28 is connected in the green light circuit 13. The traffic light signal is turned on and permitted to operate in the conventional manner to successively illuminate the green lamp 11 and the red lamp 12. During the time the red lamp 12 is lit the liquid pump 20 will be in operation to slowly pump the signal fluid 19 upwards within the tube 15 to fill the entire tube during the time the red light 12 is lit. As the fluid approaches the top of the tube 15, pedestrians approaching the signal light will know that the red light is about to change to green and they will be able to determine whether or not they will have a sufficient opportunity to proceed across a crossing before the said change takes place. During the time the red light 12 is lit the suction pump 30 will also be in operation to create a partial vacuum within the tank 18.

When the red light 12 goes out the green light

11 will become illuminated, energizing the coil 28^a of the solenoid 28, this will cause the valve 25 to be opened, permitting the partial vacuum set up within the tank 18 to quickly draw the signal fluid 19 contained within the tube 15 back into the tank 18. The solenoid 28 will remain energized during the period of time that the green light is lit and will become deenergized when the green light goes out, permitting the spring 29 to draw the valve 25 back to its closed position. When the green light 11 goes out, the red light 12 will become lit again energizing the liquid pump 20, the suction pump 30, and the lamp 32 to again pump the fluid 19 upwards within the tube 15 to repeat the procedure hereinabove outlined.

According to the modification of the invention shown in Fig. 7, the construction of the safety timing traffic light is similar to that previously described except for the fact that the glass tube 15' for the signal fluid 19 assumes a zigzag vertically extended contour.

In other respects this form of the invention is similar to that previously described and like reference numerals are used for identifying the like parts in each of the several views.

According to the modification of the invention shown in Fig. 8, the construction of the timing device is similar to that previously described except for its application to a traffic light signal 10' having a four sided operation. That is, each of the four sides of the casing 10' of the traffic signal light is provided with a green light 11 and a red light 12. Thus there is a safety traffic light device provided for each of the groups of lights for the purpose of successively indicating to pedestrians and to motorists approaching from different directions the amount of time that the red light will be lit before again turning to green. In this form of the invention there are two safety timing traffic light devices, each characterized by a tube 15' and each having a separate operating mechanism as outlined in the previous form of the invention. The construction is such that only one tube 15' will be in operation at any one time.

In other respects this form of the invention is similar to that previously described and like reference numerals are used for identifying like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits.

2. In combination with a traffic light having a green light control circuit and a red light control circuit, a tube for a signal fluid, a tank for storing a signal fluid, a signal fluid in said tank, a

pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, said signal fluid being red and means for illuminating the same while rising within said tube to be visible at night.

3. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, said signal fluid being red and means for illuminating the same while rising within said tube to be visible at night, said illuminating means comprising a lamp mounted within the base of said tube and connected in

20 said red light control circuit for being illuminated during the time said red light control circuit is in operation.

25 4. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by one of said circuits, said means comprising a radial arm extending from said valve, and a solenoid mounted in said green light circuit to direct said radial arm to open said valve during the time said green light is lit.

30 5. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by one of said circuits, said means comprising a radial arm extending from said valve, and a solenoid mounted in said green light circuit to direct said radial arm to open said valve during the time said green light is lit.

35 6. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, and means for creating a suction within the top portion of said tank to quickly draw said signal fluid back into said tank during the time said valve is open.

40 7. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, and means for creating a suction within the top portion of said tank to quickly draw said signal fluid back into said tank during the time said valve is open, said means comprising a suction pump connected in said red light circuit to operate during the time said red light circuit is in operation.

45 8. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, and means for creating a suction within the top portion of said tank to quickly draw said signal fluid back into said tank during the time said valve is open, said means comprising a suction pump connected in said red light circuit to operate during the time said red light circuit is in operation.

50 9. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, and means for creating a suction within the top portion of said tank to quickly draw said signal fluid back into said tank during the time said valve is open, said means comprising a suction pump connected in said red light circuit to operate during the time said red light circuit is in operation.

55 10. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, and means for creating a suction within the top portion of said tank to quickly draw said signal fluid back into said tank during the time said valve is open, said means comprising a suction pump connected in said red light circuit to operate during the time said red light circuit is in operation.

70 11. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, and means for creating a suction within the top portion of said tank to quickly draw said signal fluid back into said tank during the time said valve is open, said means comprising a suction pump connected in said red light circuit to operate during the time said red light circuit is in operation.

circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, said tube having a wavy contour.

8. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, said tube having a zigzag contour.

9. In combination with a traffic light having a green light control circuit and a red light control circuit, a tube for a signal fluid, a tank for storing a signal fluid, a signal fluid in said tank, a pump

for pumping said signal fluid into said tube filling the tube from the bottom upwards and set into and out of operation by one of said circuits, a drain from the bottom of said tube to said tank, a valve closing said drain, and means for operating said valve controlled by the other of said circuits, said tube and operating mechanism being duplicated for use upon a conventionally constructed traffic light signal having successively operated sides.

10. In combination with a traffic light having a green light control circuit and a red light control circuit, a tube for a signal fluid, a tank for storing a signal fluid, a signal fluid in said tank, a pump for pumping said signal fluid into said tube filling the tube from the bottom upwards and set into and out of operation by one of said circuits, a drain from the bottom of said tube to said tank, a valve closing said drain, and means for operating said valve controlled by the other of said circuits, an auxiliary tank, and means for conveying signal fluid spilling from the top of said tube back to said auxiliary tank.

ELEANOR McGUINNESS.
